UNITED STATES PATENT OFFICE.

JOHN BERNARD CLARK, OF CLEVELAND, OHIO.

METHOD OF HANDLING SLAG, CINDER, &c.

No. 926,242.

Specification of Letters Patent. Patented June 29, 1909.

Application filed September 2, 1908. Serial No. 451,378.

To all whom it may concern:

Be it known that I, JOHN BERNARD CLARK, of Cleveland, Cuyahoga county, Ohio, have invented a new and useful Method for Handling Slag, Cinder, &c., of which the following is a full, clear, and exact description, reference being had to the accompanying drawings, forming part of this specification, in which—

10 Figure 1 is a perspective view of my apparatus with a skull or cinder in place to be acted upon; and Fig. 2 is a perspective view showing the corners of the net engaged by the hooks of a traveling crane.

15 My invention relates to the handling of slag and mill cinder and its reduction in such form as can be used commercially.

It is the common practice when slag or mill cinder is removed from converters or 20 furnaces to carry it away in suitable cars or conveyances, after it has hardened, to a cinder dock where the cinder from the car is dumped to the ground. The cinder is then broken up so as to recover any scrap

25 which may be therein and to reduce it to suitable sizes for commercial use. If it is to be put to further use, it is then shoveled by hand into a suitable vehicle for removal; but it is the practice of many plants, owing

30 to the expense of treating the cinder in this way, and the discomfort and danger to the workmen from the cinder which is still hot, to carry it to a dump where it is allowed to accumulate and the scrap is not recovered.

35 By my method, I am able to readily handle and dispose of the slag and cinder and to recover any scrap which may be therein in a cheap, inexpensive and efficient manner.

In accordance with my invention, the 40 broken or partially broken slag or cinder is placed on a flexible metallic net and is crushed or broken thereon in any suitable manner as by the use of an ordinary skull cracker. The net is then gathered up 45 around the crushed slag and rings at its corner portions are engaged with the chain hooks of a traveling crane. The net with its contents is then carried by the crane to any desired place of deposit, or to any suitable conveyance, and the contents dumped by disengaging one or more of the corner rings.

In the drawings, the numeral 2 designates

the flexible metallic net, which is preferably composed of a plurality of meshed or interwoven chains, connected to outer or bounding chains 3. The latter are connected at their corner portions by rings 4, which also serve as means for the engagement therewith of the hooks 5 of the crane chains 6. 55 60 65 7 indicates the usual ball or breaker of any usual form of skull cracker.

In operation, the slag net 2 is first spread upon the ground, the cinder dumped upon it from the car or conveyer and the heavy 65 skull cracker ball or breaker 7 is then dropped upon the slag to break it up into sizes suitable for commercial use, and to enable the scrap to be extracted. The net 2 is then gathered up around the crushed material and is picked up by the crane and dumped into a suitable conveyance to be carried away for further treatment, or may be dumped at any desired point. The flexible net may be constructed in various ways 70 75 and any suitable crane may be employed for handling the net and its contents.

The advantages of my invention will be apparent since I avoid the necessity for shoveling or other manual handling of the 80 crushed slag or cinder, and thereby effect a very great saving of both time and labor.

I claim:

1. The method of handling slag or mill cinder, which consists in placing unbroken 85 slag or cinder upon a flexible metallic net, crushing or breaking the slag on the net, then gathering up the net around the crushed or broken slag, and then conveying the net with the crushed material therein to the desired point and dumping it, substantially as described.

2. The method of handling slag or mill cinder, which consists in crushing it upon a metallic flexible net, and then taking up the 95 net with the crushed material therein, and conveying the net and the material therein to the desired point, substantially as described.

In testimony whereof, I have hereunto set 100 my hand.

JOHN BERNARD CLARK.
